PLASTER CUTTING TOOL

Ernest Amundsen, New York, N. Y.

Application December 26, 1939, Serial No. 311,654

5 Claims. (Cl. 72—138)

This invention relates to a plaster cutter or plaster cutting tool and it is one object of the invention to provide a tool which will be found very useful by plasterers, and by means of which plaster may be cut along a crack in a wall to open the crack and thus form a crevice of such width and depth that plaster may be applied and firmly held in place for closing the crack when it has set and hardened.

Another object of the invention is to provide a tool of this character which may be easily held in a person's hand and moved along a crack in a wall, first with a blade presented in engagement with the wall to penetrate the plaster and deepen and somewhat widen the crack, another blade being then disposed in position to enter the deepened crack and not only additionally widen the crack or crevice but also slice through plaster along the sides of the crack and undercut the crack. It will thus be seen that a crevice of sufficient width to receive plaster may be formed and this crevice undercut so that when plaster is forced into the crevice with a trowel and allowed to harden, the applied plaster will be of dovetailed formation in cross section and prevented from working loose and dropping out of place.

A further object of the invention is to provide a plaster cutting tool which is so formed that it may be very easily held in a person's hand and prevented from turning in the hand while it is in use.

And the invention has as a still further object to provide a plaster cutting tool which is of unitary construction and includes a shank having a head at its front end formed with blades disposed in such relation to each other that one blade will not be in the way when another is in use.

The invention is illustrated in the accompanying drawing, wherein:

Figure 1 is a perspective view of the plaster cutting tool.

Figure 2 is a side elevation of the plaster cutting tool.

Figure 3 is a view looking at the head of the tool from the left of Figure 2.

Figure 4 is a view looking down upon the head of the tool.

This improved plaster cutting tool has a head 1 formed with a widened and flattened lower portion or neck 2 from which extends a shank 3 of such length that it may be conveniently held in a person's hand. The shank is tapered to a

point 4 at its lower end so that it may be driven into a handle if so desired.

A blade 5 is carried by the head 1 and extends from one side of the outer end of the head at an angle of approximately forty degrees. This blade is of triangular formation and, while it tapers to a point at its outer end, its side edges are curved longitudinally, as shown in Figures 1 and 4. It should also be noted that the side edge faces of the blade are beveled and have cutting edges 7, a cutting edge 8 being also formed at the outer end of the blade. By so forming the blade 5, a crack in the plastering of a wall may be easily followed and pressure applied by a finger disposed against the flattened portion 2 will cause the blade to penetrate the plaster and form a deep and wide channel or recess.

At the opposite side of the head from the blade 5, there has been formed a blade 9 reinforced by a depending web 10 which is integral with the blade and constitutes part of the blade. The blade and its web 10 have their opposed side faces concaved, as shown at 11, and, upon referring to Figure 3, it will be seen that the side faces of the web converge downwardly to intersect and form a diagonally extending cutting edge 12, shoulders 13 and 14 being formed at the upper and lower ends of the cutting edge 12. The blade 9 projects forwardly beyond the shoulder 13 of the web to provide a spur 15 having converging side edge faces 16 which intersect to form a sharp point for the outer end of the spur. The upper face of the blade 9 and its spur 15 are curved longitudinally, as shown in Figure 2, thus permitting rocking motion to be imparted to the tool when the blade 9 is in use, if so desired. As the side edges of the blade 9 are sharp, these edges may be used for cutting or scraping during use of the tool.

When the tool is in use, it is held in a person's hand with a finger engaging the flattened portion 2. The point 8 of the blade is applied to the wall at the crack in the plaster and the tool moved along the crack. During this movement, the blade penetrates the plaster and, as it is of triangular shape, the crack will be widened and deepened to form a channel or crevice of sufficient depth to hold plaster. The tool is then turned to bring the blade 9 into position for use

and moved through the crevice longitudinally thereof, and during this movement, the prong 15 will serve to cut out the inner portion of the crevice and the sharp edge 12 will serve to trim the side walls of the crevice. Therefore, the crevice may be undercut to form a crevice having

a restricted mouth and, when plaster is applied to fill the crevice and allowed to set and harden, the crevice will be filled with a hard plastic filling which is substantially dovetailed in cross section and thus prevented from working loose and dropping out of the crevice. The fact that the side faces of the blade 9 and the web are concaved permits undercutting to be very effectively carried out and since the upper face of the blade is curved longitudinally, permits rocking motion to be imparted to the tool for ejecting hard lumps of plaster pried loose during formation of the crevice. If so desired, the prong 15 may be first disposed in engagement with the wall and moved along the crack to form a shallow groove which will then be widened and deepened by the blade 5 to form a crevice which is to be dug out and undercut by means of the blade 9, the spur 15 and the sharpened edge 12 of the web.

Having thus described the invention, what is claimed is:

1. A tool of the character described comprising a head having a flattened lower portion for engagement by a finger and a shank extending therefrom, said head defining a laterally extending blade and a web under the blade, the blade and web having concaved side faces converging downwardly and intersecting to form a diagonally extending lower cutting edge for the web, said blade having a longitudinally curved upper surface and having its outer portion projecting beyond the web to form a spur tapered to a point at its outer end.
2. A tool of the character described comprising a head, said head defining a laterally extending blade having a depending web formed integral therewith and terminating in spaced relation to the outer end of the head, the blade and head

5 having concaved side faces converging downwardly and intersecting to form a sharp lower edge extending outwardly at an upward incline, the protruding outer portion of said blade constituting a spur gradually reduced in thickness and having its side edge faces converging and intersecting at its outer end to form a sharp point.

10 3. A tool of the character described comprising a head, said head defining a laterally extending blade and a depending web under the blade, said blade and web having concaved side faces converging downwardly and intersecting to form a sharp cutting edge along the lower end of the web, and said blade being formed with a longitudinally convexed upper face and having its outer end portion projecting beyond the web and forming a spur having side edge faces converging and intersecting at the outer end of the spur to form a sharp penetrating point.

15 4. A tool of the character described comprising a head, a shank extending from the rear end of said head, said head defining a laterally extending blade having a longitudinally curved outer end face, and a web formed integral with said blade and the shank in depending relation to the blade, the blade and web having concaved side faces converging downwardly and intersecting to form a sharp cutting edge along the lower edge of the web.

20 5. A tool of the character described comprising a head, a shank extending from the head, said head being formed with a laterally extending blade tapered to a point at its outer end, and a web depending from said blade and sharpened 25 along its lower edge.

30 35 ERNEST AMUNDSEN.
